STORM SASH

Charles H. Hucke, St. Louis, Mo.

Application November 15, 1947, Serial No. 786,281

3 Claims. (Cl. 160—210)

1

This invention relates generally to window structures and more specifically to so-called storm sashes which are adapted for application to window structures where additional protection is required to meet conditions of severe cold weather, the predominant object of the invention being to provide a storm sash structure which is of such improved construction and arrangement that it may be associated with a window structure, or removed from such association, in a simple and convenient manner, and wholly from within a room, without the use of tools or the possession of any mechanical aptitude on the part of a person performing the task.

Fig. 1 is an inside elevational view of a window structure having the improved storm sash structure of the present invention applied thereto, portions of the window sashes of the window structure being broken away.

Fig. 2 is a vertical section taken on line 2—2 of Fig. 1.

Fig. 3 is an enlarged, fragmentary vertical section taken on line 3—3 of Fig. 1.

Fig. 4 is an enlarged, fragmentary horizontal section taken on line 4—4 of Fig. 1.

Fig. 5 is an enlarged, fragmentary, elevational view of a portion of the improved storm sash structure of the present invention.

Fig. 6 is a vertical sectional view taken on line 6—6 of Fig. 5.

Fig. 7 is an enlarged, fragmentary, vertical sectional view taken on line 7—7 of Fig. 1.

Fig. 8 is a fragmentary sectional view showing a modified form of the invention.

Fig. 9 is a vertical sectional view of a window screen which may be incorporated as a part of the improved structure of the present invention.

In the drawings, wherein are shown for purposes of illustration, merely, two embodiments of the invention, A designates in Figs. 1 and 2 a window structure generally. The illustrated window structure A includes a suitable frame B which comprises side, top and bottom members C, D and E, an inner sill F, an outer sill G, and the usual inside trim H. The frame B supports an upper sash J and a lower sash K, these sashes being adapted for vertical sliding movement relative to the window frame in the usual manner in guideways provided by the window frame.

The improved storm sash structure S of the present invention comprises a pair of sashes, there being an upper storm sash 1 and a lower storm sash 2. The storm sashes 1 and 2 are of rectangular construction, each of said storm sashes comprising a frame made up of opposed

2

side members 3 and top and bottom members 4 and 5, the bottom member 5 of the upper storm sash 1 and the top member 4 of the lower sash 2 comprising meeting rails which abut against each other, to provide a storm sash structure that extends from the top to the bottom of the window structure. As is shown in Fig. 2, the bottom member of the top storm sash 1 has fixed thereto a strip of material 6 which provides a drip molding, this strip of material extending from side to side of the storm sash structure and overlapping the joint between the meeting rails provided by the bottom and top members of the upper and lower storm sashes so as to exclude moisture from said joint.

The upper and lower storm sashes of the improved storm sash structure of the present invention are connected together by a pair of coil springs 7 which are located at opposite sides of the storm sash structure and inwardly thereof. The upper ends of the coil springs 7 are engaged by hook-shaped elements 8 which are anchored to the opposed side members of the upper storm sash, while the lower ends of said coil springs are engaged by hook-shaped elements 9 which project outwardly from plates 10 that are secured to the opposed side members of the lower storm sash, these plates 10 having offset lower portions 11 which provide finger grips adapted to facilitate handling of the lower storm sash when same is being introduced into, or removed from, its operative position relative to the window structure A. The coil springs are stretched when being applied to the hook-shaped elements 8 and 9 and therefore said coil springs are maintained under tension when the storm sash structure is in its assembled condition. As a result of this situation the abutting faces of the meeting rails of the upper and lower storm sashes are drawn into close contact by the coil springs so as to provide a tight joint between said meeting rails.

When the storm sash structure S of the present invention is disposed in its effective position relative to a window structure, it is disposed within the outer portion of the frame B of said window structure, as shown to good advantage in Fig. 2. When so located a face portion of the top member of the upper storm sash contacts with an element 12 of the window structure frame B, while face portions of the opposed side members of the upper and lower storm sashes contact with opposed side elements 13 of the window structure frame which are related to said element 12. Also, a face portion of the bottom member of the lower

storm sash contacts with an outer face of the bottom member E of the window structure frame B.

Secured to the element 12 at the top of the window structure frame B is a pair of elements 14 which are of angular formation as is shown to good advantage in Fig. 3, a horizontally extended leg of each of said elements 14 being secured by suitable fastening devices to said element 12 at the lower face thereof, and an integral vertical leg of each element 14 being extended downwardly from said horizontal leg thereof. The top member of the upper storm sash 1 has fixed thereto a pair of friction devices 15 which cooperate with the elements 14 in a manner to support the upper storm sash 1 in its elevated position relative to the window structure frame while the storm sash structure is being installed. Each of the devices 15 comprises a strip of inherently resilient material which is shaped in plan as is shown in Fig. 4; that is to say said strip of material is provided with opposed flanges 16 that are secured to the top member of the upper storm sash by suitable fastening devices. Projected from the inner ends of the flanges 16 are inclined, outwardly extended walls 17 that are joined by a bridge portion 18, and extended inwardly and downwardly from the top edge of said bridge portion 18 is an integral, spring tongue 19.

When the upper storm sash is being installed in place it is moved upwardly in its proper position within the window structure frame, and as the upper storm sash approaches its ultimate elevated position within the window structure frame the vertical legs of the elements 14 are caused to be projected into the devices 15 with the result that the spring tongues 19 of said devices 15 forcibly engage said vertical legs of said elements 14. Thus, because of the pressure exerted by the spring tongues 19 of the devices 15 against the vertical legs of the elements 14, the upper storm sash is supported in its elevated position so that there is no need for fastening or attempting to hold it in such position while the lower storm sash is being installed.

The improved storm sash structure of the present invention includes, also, means for supporting the upper storm sash 1 when the storm sash structure has been completely installed in place relative to a window structure. This means comprises a pair of bracket members 20 which are secured to the opposite side elements 13 of the window structure frame B. Each of the bracket members 20 comprises a flat plate portion 21 which is arranged in contact with a face of one of the opposed side elements 13, said plate portion having vertically extended slots 22 formed therein through which the shanks of screws 20a are extended, said screws being screwed into the element 13 to which the bracket member is anchored and the heads of the screws being drawn into tight, gripping contact with the outer face of the plate portion 21 (Figs. 5 and 6). Each bracket member includes a web 23 which extends outwardly from the plate portion thereof, and the horizontal top edge portion of this web is shaped to provide an outwardly curved lip 24. Also, the plate portion of each bracket member is provided at its lower end with a lateral extension 25 which may be tapped by a hammer or other suitable instrument when the bracket member is being installed so as to locate the bracket member at its proper elevation.

Cooperating with the bracket member 20 is a pair of latching elements 26 which are supported

by the upper storm sash 1. Each latching element 26 comprises a member having a horizontal extension 27 from which a vertical extension 28 is extended upwardly, the latching element being supported by the upper storm sash for pivotal movement by a screw 29 which extends through an opening formed through the upper portion of the vertical extension thereof and is screwed into the upper sash. Each latching member 26 includes, also, an extension 30 which is projected downwardly from the horizontal extension 27 in vertical alignment with the upwardly projected extension 28, this downwardly projected extension being offset outwardly so as to be provided at its top with a horizontal wall portion 31 (Fig. 6) which joins said extension 30 with the main body of the latching element 26. The lower portion 32 of the downwardly projected extension 30 of each latching element 26 is bent inwardly, as is shown in Fig. 6, and, also, each latching element is provided with an outwardly extended finger grip 26' which facilitates rotary actuation of said latching element. Additionally, each latching element 26 is provided with an upper pair of spaced flanges 33 that extend outwardly from the extension 28, and a lower pair of similar spaced flanges 34 that extend outwardly from the extension 30. The upper and lower spaced flanges are aligned vertically with each other when the latching elements are in their normal latching positions and the coil springs 7, previously referred to herein, extend between the flanges of said pairs of flanges, as is shown in Fig. 1.

When the upper storm sash 1 is being introduced in place with respect to a window structure, the latching elements are moved to the position indicated by dotted lines in Fig. 5. The upper storm sash is then moved upwardly in its proper position within the window structure frame until the vertical legs of the elements 14 extend into the devices 15 of said upper storm sash whereby the upper storm sash is frictionally retained in place. With the upper storm sash held in its proper position relative to the window structure frame, the latching elements are moved to their normal positions where the horizontal wall portions 31 of said latching elements engage and rest upon the lips 24 of the bracket members 20 (Fig. 6). Thus, the upper storm sash is positively latched in its proper elevated position by the cooperation of the latching elements and the bracket members, so that tight contact is made between the upper edge of said upper storm sash and a related portion of the window structure frame. Attention is directed to the fact that the bent portions 32 of the latching elements 26 are adapted to abut against edges 23' of the webs 23 of the bracket members to arrest rotary movement of said latching elements when they have reached their normal positions. Also, because the coil springs 7 extend between the flanges 33 and 34 of the latching elements 26, said latching elements are held against accidental rotary movement when the upper and lower storm sashes are in place and the coil springs 7 are associated therewith.

The lower storm sash 2 is provided at its top with an element 35 that extends longitudinally of the upper horizontal rail of said lower storm sash, and fixed to this element 35, preferably at the longitudinal center thereof, is a safety guide 36. This safety guide is shaped in cross-section as is shown in Fig. 7 wherein it is shown as being provided with angularly related portions 37

which contact with the top and outer faces of said element 35 and as having an upwardly extended portion 38, the upwardly extended portion 38 of the safety guide 36 contacting with a plate 39 which is secured to the lower meeting rail of the upper storm sash inwardly thereof. The function of the safety guide is to prevent the upper portion of the lower storm sash from accidentally swinging outwardly and getting out of control when said lower storm sash is being installed or removed, the engagement of the upwardly extending portion 38 of the safety guide with the lower meeting rail of the upper storm sash preventing such accidental outward movement of the upper portion of the lower storm sash.

The storm sash structure of the present invention includes locking devices 40 for locking the upper and lower storm sashes in position with respect to the window structure frame B. These locking devices may be of any suitable type which will draw said storm sashes into tight lateral engagement with the parts of the window structure frame with which said storm sashes contact, one type of locking device which is well adapted for this purpose being the locking device disclosed in an application for patent filed in my name on February 16, 1946, Serial No. 648,175. Also, if desired the lower storm sash may have swingably associated therewith an elongated hook 41 which may be employed to retain the lower storm sash in an open position at its bottom for ventilating purposes, as is shown by dotted lines in Fig. 2.

An important feature of the storm sash structure of the present invention is that a full-length storm sash may be converted into one of the improved sash structures by sawing the full-length storm sash in half to provide an upper and a lower storm sash. When this is done the intermediate horizontal rail of the full-length storm sash is sawed longitudinally so as to provide the two resultant storm sashes with meeting rails, and the drip mold 6 is secured to the upper storm sash so produced so that it will overlap the joint between said meeting rails, as has been previously explained herein and as is shown in Fig. 2. When a full-length storm sash is cut in half to produce the improved storm sash structure, the meeting rails of the storm sashes 1a and 2a so produced may be prepared as shown in Fig. 6. In accordance with the showing of this view the meeting rail of the upper storm sash 1a may have secured to its lower edge a strip of material 42 which extends throughout the entire area of said lower edge, said strip of material having a drip mold 43 associated therewith. Also, the top edge of the meeting rail of the lower storm sash may have fixed thereto a strip of material 44 that extends throughout the entire area of said top edge, this strip of material 44 having associated therewith an element 45 which corresponds to the element 35 heretofore referred to herein and illustrated to good advantage in Fig. 2.

It is obvious that during periods of warm weather the lower storm sash 2 of the improved storm sash structure may be replaced by a window screen 46 (Fig. 9). The window screen 46 is constructed in accordance with the lower storm sash of the storm sash structure except that it is provided with screening instead of a pane of glass.

From the foregoing it is plain that the storm sash structure of the present invention is light in weight and of simple construction so that it

may be installed or removed quickly and easily without the need for tools or mechanical skill on the part of the person performing the operation. Also, the improved storm sash structure may be installed or removed entirely from within a room, thus eliminating the need for the climbing of ladders on the outside of a building.

I claim:

1. The combination with a window structure having a window frame adapted to support window sash means, of an auxiliary protective means comprising upper and lower sash-like members arranged within an outer portion of said window frame in vertical alinement, said sash-like members having meeting rails that are disposed in abutting relation, a pair of coil springs disposed adjacent to opposite side edges of said sash-like members and connected at their opposite ends to the respective sash-like members, said coil springs being adapted to draw abutting edges of said meeting rails of said sash-like members into close contact, and means for supporting said upper sash-like member relative to said window frame, said supporting means comprising a pair of elements supported for pivotal movement by said upper sash-like member at opposite sides thereof, and a pair of bracket members that are fixed to said window frame at opposite sides thereof, the pivotally supported element at each side of said upper sash-like member being adapted for movement into engagement with the bracket means at the corresponding side of the window frame for supporting said upper sash-like member, and spaced projections formed on said pivotally supported elements between which said coil springs are extended.
2. The combination with a window structure having a window frame adapted to support window sash means, of an auxiliary protective means comprising upper and lower sash-like members arranged within an outer portion of said window frame in vertical alinement, said sash-like members having meeting rails that are disposed in abutting relation, a pair of coil springs disposed adjacent to opposite side edges of said sash-like members and connected at their opposite ends to the respective sash-like members, said coil springs being adapted to draw abutting edges of said meeting rails of said sash-like members into close contact and means for supporting said upper sash-like member relative to said window frame, said supporting means comprising a pair of elements supported for pivotal movement by said upper sash-like member at opposite sides thereof, and a pair of bracket members that are fixed to said window frame at opposite sides thereof, the pivotally supported element at each side of said upper sash-like member being adapted for movement into engagement with the bracket means at the corresponding side of the window frame for supporting said upper sash-like member, and spaced outstanding projections formed on said pivotally supported elements between which said coil springs are extended.
3. The combination with a window structure having a window frame adapted to support window sash means, of an auxiliary protective means comprising upper and lower sash-like members arranged within an outer portion of said window frame in vertical alinement, said sash-like members having meeting rails that are disposed in abutting relation, a pair of coil springs disposed adjacent to opposite side edges of said sash-like members and connected at their opposite ends to the respective sash-like members, said

coil springs being adapted to draw abutting edges of said meeting rails of said sash-like members into close contact and means for supporting said upper sash-like member relative to said window frame, said supporting means comprising a pair of elements supported for pivotal movement by said upper sash-like member at opposite sides thereof, and a pair of bracket members that are fixed to said window frame at opposite sides thereof, the pivotally supported element at each side of said upper sash-like member being adapted for movement into engagement with the bracket means at the corresponding side of the window frame for supporting said upper sash-like mem- 10

ber, and pairs of vertically aligned and horizontally spaced projections formed on said pivotally supported elements between which said coil springs are extended.

CHARLES H. HUCKE.
